CLAIM

The ornamental design for a genie lamp, as shown and described.

DESCRIPTION

FIG. 1 is a front, left, top perspective view of a genie lamp embodying our new design;

FIG. 2 is a front plan view thereof;

FIG. 3 is a back plan view thereof;

FIG. 4 is a left-side plan view thereof;

FIG. 5 is a right-side plan view thereof;

FIG. 6 is a top plan view thereof; and,

FIG. 7 is a bottom plan view thereof.

The broken lines shown in the drawings are included for the purpose of illustrating portions of the genie lamp and form no part of the claimed design.
